GARMENT

Florence Z. Walsh, Hyde Park, N. Y.

Application June 15, 1939, Serial No. 279,379

1 Claim. (Cl. 2-92)

This invention relates to improvements in garments and more particularly to garments of the waist type.

The primary object of the invention is to provide a garment of the above mentioned character known in the art as a dickey which includes an easily removable waist capable of being worn under the coat of a suit or ensemble.

A further object of the invention is to provide a waist garment or dickey having elastic waist encircling straps which prevent the front and back portions of the dickey from sliding upward and becoming unsightly in appearance.

A still further object of the invention is to provide a waist garment or dickey having a collar and neck opening for allowing the easy application and removal of the garment.

Other objects and advantages of the invention will become apparent during the course of the following description taken in connection with the accompanying drawing, wherein,

Figure 1 is a front elevational view of the dickey, illustrating the same in position on a wearer,

Figure 2 is a rear elevational view of the same illustrating the dickey in position on a wearer and showing the manner in which the back portion is applied,

Figure 3 is a side elevational view of the dickey further showing the side retaining straps,

Figure 4 is a horizontal cross sectional view taken on line 4-4 of Figure 3 looking in the direction of the arrows illustrating the manner in which the back and front portions of the dickey are secured together by the elastic side straps, and,

Figure 5 is a fragmentary front elevational view showing a modified collar construction.

In the drawing, wherein for the purpose of illustrating the invention and wherein like reference characters will be employed to designate like parts throughout the same, the reference character 6 will be employed to generally designate a waist garment or dickey including a front portion 8 and a back portion 10 connected by shoulder strap portions 11 forming a neck opening 13 having a collar 15 of the soft fold type.

The front portion 8 of the dickey may be formed of a different material than the back portion 10 but it has been found desirable to form the front and rear portions of a good grade of knitted or woven material presenting a pleasing appearance to the eye.

Secured to the lower portion of the front and back 8 and 10, respectively, is an elastic strap

17 having its ends stitched or otherwise secured in place as at 18. The opposite side is provided with a pair of elastic straps 19 and 21 secured to the front 8 by means of stitches 23 and to the back 10, as at 25, respectively. A hook fastener 27 is provided for securing the ends of the elastic straps 19 and 21 together to cause the waist portion of the dickey to snugly fit the waist of the wearer W.

It is well known that straps have been employed in the art for securing the lower portions of the front and back panels together. However, they do not function in such a manner as to cause the collar to fit properly. It has been found that the elastic straps closely embrace the waist preventing the riding up of the panels and at the same time urging the collar downwardly into embracing engagement with the shoulders effecting a graceful and comfortable fit thereof.

In Figure 5, the dickey 28 is provided with a collar 30 which is of a different form than the collar 15 and is provided with a closure flap 32 adapted to be fastened by means of a separable fastener or buttons.

The dickey 6 may be provided with suitable ornamentation on the front 8 which will be exposed through the ensemble coat to add to the aesthetic beauty of the garment and if desired, the dickey can be pressed to conform to the bosom of the wearer W.

It is to be understood that the form of the invention herewith shown and described is to be taken as a preferred embodiment of the same and that various changes in the shape, size and arrangement of parts may be resorted to without departing from the spirit of the invention or the scope of the subjoined claim.

What is claimed is:

40 A dickey for women's wear comprising a front panel and a back panel, both panels extending down to the waist line and being spaced at the sides along substantially parallel edges, said panels being joined together at the shoulders and around the neck by means of a loosely fitting collar, elastic bands connecting said panels at the lower ends of their side edges, the upward displacement of the bottom edge of said front panel from said waist line, due to the natural bust configuration of the wearer causing a stress in said elastic bands and a resulting downward pull on the side edges of said front panel, thereby holding the upper portion of said dickey, including said collar, in place.
